UNITED STATES PATENT OFFICE.

PAUL SCHUYLER VAN BLOEM, OF HEMPSTEAD, NEW YORK, ASSIGNEE TO THE VIKING PRODUCTS CORPORATION, OF NEW YORK, N. Y., A CORPORATION OF NEW YORK.

SIGN.

Application filed November 24, 1922. Serial No. 603,013.

To all whom it may concern:

Be it known that I, PAUL SCHUYLER VAN BLOEM, a citizen of the United States, and resident of Hempstead, in the county of 5 Nassau and State of New York, have invented certain new and useful Improvements in Signs, of which the following is a specification.

One of the main objects of this invention is the provision of a sign or signal plate of translucent glass, or other material which will permit the passage of light rays, having sign or signal characters formed by depressions in the rear or light 10 receiving face of the plate and by convexities upon the front face of the plate. The convexities overlie the depressions and both conform in outline to the sign or signal character. The walls of the depressions are so shaped and disposed as to cause most of the light rays entering the 15 depressions to be concentrated and directed outwardly through the convexities and also to produce a shaded effect which will give 20 the characters a decided outstanding appearance upon the front face of the plate. The convexities distribute the illumination properly over the front portions of the characters and also increase the range of 25 visibility of the characters by the reflection of light from the outside.

In the drawings:

Fig. 1 is a front elevation of a signal showing the plate adapted for use therein;

Fig. 2, a vertical section taken through the signal on the line 2—2 of Fig. 1;

Fig. 3 a greatly enlarged detail section taken through the plate on the line 3—3 of Fig. 1;

Fig. 4 a fragmentary view of the rear face of the signal plate; and

Fig. 5 a view similar to Fig. 3 showing a coat of coloring or opaque matter applied to the bottom of the depression.

Referring to the parts by numerals, 1 designates the improved sign or signal plate. The plate 1 is made of transparent or translucent glass or other suitable material which will permit the passage of light rays and has substantially flat, parallel, front and

reverse faces 2 and 3 respectively. A series of deep character impressions 4 are formed in the reverse face of the plate and a series of convexities 5 are formed upon the front face 2 of the plate. The convexities 5 55 overlie the depressions 4 and both the convexities and the depressions conform in outline to the characters to be displayed. In the present instance the plate 1 is adapted for use as an elevator signal and the characters are the letters of the word "Down." The plate is larger than the over-all dimensions of the characters in order to secure a general illumination of that part of the plate surrounding the characters. The plate 60 is shown in Figs. 1 and 2 as mounted in a casing 6, the said casing preferably having a rear reflecting wall 7. A lamp 8 is suitably located and mounted within the casing to properly illuminate the plate. It will, of 65 course, be understood that the lamp and signal plate could be mounted in other ways than the one shown.

In the present instance the depressions 4 and the convexities 5 form the strokes of 75 a letter. Each of the said depressions is formed with side walls 9 which in cross section are straight, as shown in Fig. 3, and are substantially perpendicular to the plate face 3. The bottom 10 of the depression 80 curves inwardly at the sides as shown at 11 and merges with the side walls. The side walls 9 are of material depth particularly with relation to the width of the letter stroke, and this depth of the side walls and 85 their substantial perpendicularity to the face 3 of the plate together with the convexities 5 are important factors in producing the effect of a decidedly outstanding character upon the front face of the plate. 90

The effect of the light rays which are directed from the rear into the depressions 4, as illustrated in Fig. 4, is as follows, assuming that the signal is viewed from directly in front: The ray *a* which passes 95 through the center of the depression and through the center of the convexity 5 will be unrefracted and will pass straight to the eye of the observer. The rays *b* at either side of *a* are slightly refracted but emerge 100

from the convexity 5 substantially parallel to the rays *a*; the rays *a* and *b* are thus distributed fairly evenly over the surface of the convexity and are directed toward the eye of the observer. The rays *c* and *d* which fall upon the curves 11 of the depression diverge away from the eye of the observer with the result that the sides of the character will appear shaded. Owing to the substantial perpendicularity of the walls 9 to the rear face of the plate most of the rays *e* incident thereon will be beyond the critical angle or the angle at which they would penetrate the plate and will therefore be reflected to, and be concentrated at, the bottom of the plate from whence they will be transmitted through the convexity. The side walls of the depressions diverge slightly and this divergence tends to increase the shaded effect at the edge of the character when viewed from the front, and also facilitates the withdrawal of the mold used in forming the depressions.

When the signal is viewed obliquely as from the direction indicated by the right hand arrow in Fig. 3, the rays such as *b* and *c* which are cast upon the curve 11 of the depression are directed toward the observer while the rays *a* and *b* which fall upon the bottom 10 and pass through the convexity 5 are directed away from the observer as are also the rays *e* which fall upon the side walls 9. The result will be that the character will appear as an outstanding perspective with a high light at the corner due to the rays coming through the curve 11 and with the convexity 5 and the nearer side wall 9 of the depression shading off from either side of the high light.

In Fig. 5 the bottom 10 of the depression 4 is shown as provided with either a colored or an opaque coating 12 to produce a desired ornamental effect. The coating 12 may be applied to only the center of the bottom 45 leaving the curves 11 uncovered so as not to diminish their effect.

It will be seen that a simple, easily manufactured sign or signal and one that is also beautiful and effective, is provided. A signal of this character which permits the light to pass through the entire area of the plate is particularly effective as it makes a more striking effect and will attract more attention than if merely the characters were illuminated. The convexities 5 serve to make the characters more distinct and legible particularly when viewed obliquely as the said convexities reflect toward the observer light which they receive from the surroundings.

A sign of this character is effective even when used independently, without the special illumination shown in Fig. 2. When unprovided with special illumination the sign will share in the general illumination, either daylight or artificial, of its surround-

ings, the depressions 4 and the convexities 5 rendering the characters distinct from the rest of the plate.

What I claim is:

1. A sign plate of material adapted to permit the passage of light rays, formed in its rear face with a depression and formed on its front face with a convexity overlying the depression, the convexity and the depression being alike in outline and forming a sign character, the said depression having a bottom designed to transmit light rays through the convexity and a pair of reflecting side walls of material depth and substantially perpendicular to the rear face of the sign plate.

2. A sign plate of material adapted to permit the passage of light rays, formed in its rear face with a depression of material depth and formed on its front face with a convexity overlying the depression, the convexity and the depression being alike in outline and forming a sign character, and the said depression being formed in cross section with a bottom and a pair of straight side walls the said bottom and side walls being so disposed as to concentrate light rays falling within the depression and direct them through the convexity.

3. A sign plate of material adapted to permit the passage of light rays, formed in its rear face with a depression and formed upon its front face with a convexity overlying the depression, the convexity and the depression being alike in outline and forming a sign character, and the said depression having a bottom, side walls so disposed as to reflect light rays upon the bottom and surfaces at the juncture of the side walls and the bottom so disposed as to cause light rays cast thereon to be refracted away from the center.

4. A sign plate of material adapted to permit the passage of light rays, formed in its rear face with a depression of material depth and formed upon its front face with a raised portion overlying the depression, the raised portion and the depression being alike in outline and forming a sign character, the plate being larger than the overall dimensions of the sign character and admitting light through its area surrounding the sign character and the depression having reflecting side walls of material depth and substantially perpendicular to the rear face of the sign plate to direct light rays through the raised portion.

5. A sign plate of material adapted to permit the passage of light rays, formed in its rear face with a depression and upon its front face with a raised portion overlying the depression, the raised portion and the depression being alike in outline and forming a sign character and the depression being of material depth with relation to its

width and adapted to concentrate light rays falling therein and direct them through the raised portion.

6. A sign plate of material adapted to permit the passage of light rays, formed in its reverse face with a depression and upon its front face with a raised portion overlying the depression, the raised portion and the depression being alike in outline and

forming a sign character, and a coating of 10 coloring matter applied to the bottom of the depression, the said depression being adapted to concentrate light rays falling therein and direct them through the raised portion.

In testimony whereof I hereunto affix my signature.

PAUL SCHUYLER VAN BLOEM.
